[57] **ABSTRACT**

A machine which spreads carton blanks on a belt conveyor and brushes loose bits of paperboard from upper and lower faces of the carton blanks and edges of the carton blanks. The carton blanks are counted and then stacked on an elevator which is gradually lowered as a stack of carton blanks builds up on the elevator. The stack is then advanced onto a discharge conveyor where an outer carton can be placed over the stack of carton blanks. Finally, the stack and the outer carton are inverted on a turntable and the outer carton with the stack of carton blanks thereinside is discharged from the machine.

MACHINE FOR BRUSHING AND STACKING CARTON BLANKS

This invention relates to a machine for brushing die cut paperboard carton blanks and for counting and stacking the carton blanks after they have been brushed and counted.

Die cut paperboard carton blanks can have associated therewith small bits of paperboard or the like which are cut from a paperboard sheet in the forming of the carton blank which small bits are undesirable, particularly if the carton blanks are to be used in forming cartons for food items or the like. An object of this invention is to provide a machine which brushes carton blanks to remove such unwanted small bits of paperboard.

A further object of this invention is to provide such a machine which counts the carton blanks after the carton blanks have been brushed and piles the carton blanks on a platform after the carton blanks have been counted.

A further object of this invention is to provide such a machine in which a pile of carton blanks containing a selected number of carton blanks is discharged onto a discharge conveyor where an outer container can be disposed over the pile of carton blanks and in which the outer container with the pile of carton blanks thereinside is turned 180 degrees into position for sealing of the outer container.

Briefly, this invention provides a machine to which carton blanks can be fed which spreads out the carton blanks on a belt conveyor. Upper and lower faces of the carton blanks and edges of the carton blanks are brushed to remove unwanted loose bits of paperboard as the carton blanks are being conveyed. The carton blanks are counted and then stacked on an elevator which is gradually lowered as a stack of carton blanks builds up on the elevator. The stack is then advanced onto a discharge conveyor where an outer carton can be placed over the stack of carton blanks. Finally, the stack and the outer carton are inverted and the outer carton with the stack of carton blanks thereinside is discharged from the machine.

The above and other objects and features of the invention will be apparent to those having ordinary skill in the art to which this invention pertains from the following detailed description and the drawings in which:

FIG. 1 is a schematic view in side elevation of a machine constructed in accordance with an embodiment of this invention;

FIG. 2 is a view in side elevation of the main portions of the machine illustrated in FIG. 1;

FIG. 3 is a fragmentary view in side elevation of a portion of the machine showing drive connections of the machine with other portions of the machine being removed for clarity;

FIG. 4 is a plan view of the portion of the machine shown in FIG. 3;

FIG. 5 is a fragmentary view in side elevation on an enlarged scale showing a brushing section of the machine, hoods for brushes being shown in dot-dash lines;

FIG. 6 is a plan view of the brushing section of the machine shown in FIG. 5;

FIG. 7 is a fragmentary view on an enlarged scale in side elevation of a counting and stacking section of the machine, a side guide being partly broken away to reveal details of construction;

FIG. 8 is a view in side elevation on an enlarged scale of an elevator section of the machine, other portions of the machine being omitted for clarity;

FIG. 9 is a plan view of the elevator section of the machine shown in FIG. 8;

FIG. 10 is a fragmentary plan view of a feed section of the machine which delivers carton blanks to the brushing section;

FIG. 11 is a fragmentary view in side elevation of the feed section shown in FIG. 10;

FIG. 12 is a view in section taken on an enlarged scale on the line 12—12 in FIG. 10;

FIG. 13 is a view in side elevation on an enlarged scale of a carton blank distributing assembly which forms a part of the machine;

FIG. 14 is a plan view of the carton blank distributing assembly shown in FIG. 13;

FIG. 15 is a plan view of a carton blank handled by the machine;

FIG. 16 is a view in end elevation of a side brush assembly forming a part of the machine, a fragmentary portion of a supporting frame element being shown in section in association therewith, fragmentary portions of conveyor belts and of carton blanks also being shown in association therewith;

FIG. 17 is a view in side elevation of the side brush assembly shown in FIG. 16;

FIG. 18 is a view in section taken on the line 18—18 in FIG. 16;

FIG. 19 is a view in side elevation on an enlarged scale showing a counting station of the machine, counter rolls being shown in operative position;

FIG. 20 is a plan view of the counting station shown in FIG. 19;

FIG. 21 is a view in section taken on an enlarged scale on the line 21—21 in FIG. 7;

FIG. 22 is a fragmentary view taken on an enlarged scale in the direction of the arrows in FIG. 8;

FIG. 23 is a fragmentary perspective view of elevator supporting mechanism of the machine;

FIG. 24 is a view in section taken on an enlarged scale on the line 24—24 in FIG. 8;

FIG. 25 is a view in side elevation on an enlarged scale of a discharge section and a carton inverting section of the machine; the carton inverting section being shown in full lines in an intermediate position, a portion thereof being shown in carton receiving position in dot-dash lines and a portion thereof in carton ejecting position being shown in double dot-dash lines;

FIG. 26 is a plan view of the discharge and carton inverting section of the machine shown in FIG. 25;

FIG. 27 is a schematic wiring diagram of the machine;

FIG. 28 is a schematic diagram of hydraulic connections of the machine;

FIG. 29 is a view in side elevation on an enlarged scale showing upper and lower brushes and brush supports of the machine;

FIG. 30 is a plan view on an enlarged scale of the portion of the machine shown in FIG. 29;

FIG. 31 is a fragmentary plan view on an enlarged scale of a valve and valve actuating assembly forming a part of the machine;

FIG. 32 is a view in section taken on the line 32—32 in FIG. 50 7;

FIG. 33 is a view in side elevation of an upper side guide of the machine;

FIG. 34 is a fragmentary plan view showing upper side guides and related parts of the machine, other parts being omitted for clarity;

FIG. 35 is a top plan view of the part of the machine shown in FIG. 30 with upper brushes and supports therefor removed; and

FIG. 36 is a view in section on an enlarged scale taken on the line 37—37 in FIG. 30.

GENERAL DESCRIPTION

In FIG. 1 is schematically shown a machine 30 constructed in accordance with an embodiment of this invention. The machine 30 includes a feed table section 31 provided with a belt 32 on which carton blanks 33 are loaded. The belt 32 advances the carton blanks 33 onto a conveyor belt system, indicated schematically at 34, on which the carton blanks pass under a carton blank distributing assembly or discriminator 35 which spreads the carton blanks in overlapping relation. The carton blanks are directed below upper brushes 37 and 38 and above lower brushes 39 and 41, each of which is opposed to and immediately under one of the upper brushes. Then the carton blanks pass to sloping or elevating belts 42 and 43

which catch the forward end of each of the carton blanks and cause the rear end thereof to swing against a bottom brush 44. The belts 42 and 43 carry the carton blanks between side brushes 46 and 46' (FIGS. 5 and 6) which brush side edges of the cartons. Then the carton blanks are carried past a counter switch 47 (FIG. 1) and, after being counted, are projected against downwardly extending actuator arms 48 of an elevator control valve 49. After engaging the actuator arms 48, each carton blank falls onto an elevator platform 51, the carton blanks forming a stack 52 thereon. As carton blanks collect in the stack 52 on the elevator platform, the platform moves downwardly until a predetermined count is reached. Then the elevator platform moves downwardly to a position indicated by dashed lines at 51', at which position a pusher 53 pushes the stack 52 of carton blanks onto a discharge conveyor 54. An outer carton 56 is placed over the stack of carton blanks, and the outer container with the stack thereinside is moved to a generally U-shaped turntable 57 which turns the container through an angle of approximately 180 degrees to the position shown at 57' whereupon the carton with the stack thereinside can be discharged as indicated at 56' onto a delivery conveyor 58 in upright position ready for closing of the container.

The machine which has been described in general terms to this point will now be described in greater detail.

FRAME AND MAIN DRIVE ARRANGEMENTS

As shown in FIG. 2, the machine 30 includes a main framework 61, a discharge conveyor framework 62 and a turntable framework 63. On the side of the main framework 61 shown in FIG. 2, the main framework 61 includes upright frames 64, 65, 66, 67 and 68, lengthwise lower frames 69, intermediate lengthwise frames 74 and 76, and upper lengthwise frame 77. Similar frames on the opposite side of the machine, not all of which are shown in detail, are indicated by like numbers to which a prime has been added. The upright frames and the lengthwise frames on opposite sides of the main framework are connected by appropriate cross frames, one of which is shown at 78 in FIG. 4, not all of which are shown in detail. The uprights 66 and 66' carry frame plates 79 and 79' (FIG. 6) between which a number of shafts are mounted, as will be indicated more fully hereinafter.

Power for operating the main belts of the machine is provided by a main drive electric motor 81 (FIGS. 3 and 4). The motor 81 is mounted on a plate 82 supported on cross frames 83 and 84. A shaft 85 of the motor 81 carries a pulley 86 (FIG. 4) which drives a belt 87. The belt 87 drives a pulley (not shown) on a shaft 88. The shaft 88 drives gears (not shown in detail) in a gear box 89 and also drives a clutch 90. The gears in the gear box 89 drive a shaft 91 which carries a drive sprocket 92. The drive sprocket 92 drives a chain 93 which runs over idlers 94, 95, 96, 97, 97' and 98 and drives sprockets mounted on shafts 99, 100 and 101.

The clutch 90 (FIG. 3) drives gears in a gear box 102 which drive a pulley 103 and a sprocket wheel 104 on a shaft 105 (FIG. 4). A belt 106 (FIG. 3) driven by the pulley 103 drives a pulley 107 mounted on a shaft 108 which also carries a sprocket 109. The sprocket 109 drives a chain 110 which drives a sprocket 111 mounted on a shaft 112. The shaft 112 carries a pulley 113 (FIG. 4) on which a belt 114 runs, which is a part of the belt system 34 of FIG. 1. The shaft 112 also carries a sprocket 116 (FIG. 3) which drives a chain 117. The chain 117 drives a sprocket 118 (FIG. 3) mounted on a shaft 119 which carries a pulley 121 (FIG. 4) which drives a belt 122, which is also a part of the belt system 34 of FIG. 1. The belt 122 also runs over idle pulleys 123 (FIG. 3) and 124. The upper course of the belt 122 is divided into an upwardly directed course portion 126 and a horizontal course portion 127. As shown in FIG. 3, the sprocket 118 is larger than the sprocket 116 so that the belt 114 moves faster than the belt 122.

The sprocket 104 drives a chain 131 which drives sprockets on drive shafts 132, 133, 134 and 136 and also runs over idle

sprockets 137, 138, 139, 140, 141, 142, 143, 144, 146, 147 and 148, as shown in FIG. 3. The drive chain 93 runs constantly while the motor 81 runs but the drive chains 131, 110 and 117 run while the clutch 90 is engaged and are stationary when the clutch 90 is disengaged.

The machine operates on carton blanks 33, a typical carton blank being shown in FIG. 15. The carton blank 33 includes a body 152, side flaps 153 and 154, and end flaps 156 and 158. Indentations 159 and 161 are formed in the paperboard 152 between flaps. The carton blank 151 is formed by die cutting from a paperboard sheet and, in the die cutting process, small portions of paperboard 162 and 163 can be retained at the indentations and elsewhere. Such small portions are undesirable because they can become mixed with articles packaged in a carton formed by erecting the carton blank into a carton. The brushes 37, 38, 39, 41, 44, 46 and 46' act to remove such unwanted small portions of paperboard.

DISCRIMINATOR ASSEMBLY

A stack 166 of carton blanks can be advanced from the feed table section 31 (FIG. 11) across a transfer table 164 to the belt 122. A belt 165 of the feed table can be advanced by operation of a motor 165' (FIG. 27) and drive connections, not shown in detail. As the upper course of the belt 122 moves to the left as shown in FIG. 11, the carton blanks of the stack come into engagement with the discriminator 35, as shown in FIG. 11, and the carton blanks are spread out on the belt 122 into overlapping relation. The carton blanks advance from the belt 122 onto the belt 114 with a small portion of each carton blank being overlapped by the succeeding carton blank on the belt 114. The discriminator 35, as shown in FIGS. 3 and 4, includes a plate-like body 167 (FIG. 3) having a lower portion 168 which extends downwardly and along the direction of belt movement to just above the belt 122 into position for engaging the carton blanks. As shown in FIGS. 13 and 14, the discriminator body 167 is mounted on bars 169 and 171. Screw fasteners 172 (FIG. 13) and 173 connect the body 167 to the bars 169 and 171. The screw fasteners 172 and 173 also extend through diametral bores in a transverse rod 174. The rod 174 is supported by upright bars 175 and 176. The bars 175 and 176 are similar in construction and only the bar 175 and supports thereof will be described in detail. The rod 174 extends through a slotted bore 177 in the upright bar 175. End portions of the upright bar 175 on opposite sides of a slot 178 thereof are drawn toward each other by a screw 179 to lock the transverse rod in position in the bore 177. The lower end of the upright bar 175 is supported between elevated frames 181 and 182. Each of the elevated frames 181 and 182 is provided with a plurality of spaced aligned transverse bores 183, and the upright bar 175 is mounted therebetween by means of a bolt 184 which extends through aligned transverse bores in the elevated frames 181 and 182 and draws the frames 181 and 182 against opposite sides of the upright bar 175 to hold the upright bar in position. The upright bar 175, however, can be swung about the bolt 184 with the transverse rod 174 and the body 167 for adjustment of the position of a lower end edge 187 of the lower portion 168 of the discriminator body 167. The height of the lower end edge 187 can be adjusted by means of an adjustment eyebolt 188. The eyebolt 188 has a head 189 (FIG. 14) which is swingably mounted on a rod 191 mounted in transverse bores 192 and 193 in the bars 169 and 171, respectively. A threaded shank 194 of the eyebolt 188 extends upwardly through an upright bore 196 (FIG. 13) in a horizontal flange 197 of an angle bracket 198. Nuts 199 and 201 on opposite sides of the flange 197 can be turned for adjusting the height of the head 189 of the eyebolt 188 and of the lower end edge 187 of the discriminator body 167. The nuts 199 and 201 can be provided with appropriate washers 202 and lock washers 203. The angle bracket 198 is attached to mounting blocks 204 and 206 which are mounted for adjustment along the elevated frames 181 and 182 and along similar elevated frames 207 and 208 (FIG. 6) on an opposite side of

the machine. Screw fasteners 209 (one of which is shown in FIGS. 13 and 14) are threaded in the blocks 204 and 206 for folding the blocks with the angle bracket 198 in adjusted position. A washer 210 mounted on the shank of the fastener 209 underlies the elevated frames 181 and 182. As shown in FIGS. 13 and 14, the right hand ends of the elevated frames 181 and 182 are supported by an upright bar 211 received and engaged therebetween by action of a bolt 212 received in aligned transverse bores of the elevated frames. A lower end of the upright bar 211 is supported on the frame 74 by means of a bracket 213 and fasteners 214 and 216 above and below the frame 74.

SIDE GUIDES

As already pointed out, after passing the discriminator assembly 35, the carton blanks pass from the belt 122 onto the belt 114. Upper courses of the belts 122 and 114 both move to the left as shown in FIGS. 3 and 11, but the upper course of the belt 114 moves faster than the upper course of the belt 122 so that the carton blanks are maintained in spread position on the belt 114 as the carton blanks advance therewith. As shown in FIG. 29, the belt 114 moves on a pulley 2161 carried by the drive shaft 112 and over idle pulleys 2162, 2163, 2164 and 2166. As the carton blanks advance on the belts 122 and 114, the carton blanks are guided into centered position on the belts 122 and 114 by upright side guides 218 and 219 (FIG. 10). End portions 221 and 222 of the side guides 218 and 219, respectively, adjacent the transfer table 164 converge inwardly to main portions thereof. The side guides 218 and 219 are supported on appropriate cross rods 223, 223' and 223'' (FIG. 11). The cross rods are carried by brackets 223' mounted on the frame 74. The side guide 218 is advanced toward or away from the belts 122 and 114 by threaded rods 224 and 224'. Details of construction of the threaded rod 224 and its support are shown in FIG. 12. An inner end of the rod 224 is mounted in a socket 225 in a swinging bracket 226. The bracket 226 is pivotally mounted on an upright pin 227 which is mounted in bifurcations 228 and 229 of a bracket 231 which is attached to the wall of the side guard 218. An outer portion of the threaded rod 224 receives an adjustment nut 232 which carries a sprocket 233. The adjustment nut 232 is rotatably mounted in bearing bores in upright bars 234 and 236, which are supported on the frame 74. Fasteners 237 and 238 mount the upright bars 234 and 236 on the frame 74. A chain 239 (FIGS. 5 and 10) which runs on the sprocket 233 also runs on a similar sprocket 241 associated with the threaded rod 224' and on a crank operated sprocket 242. Turning of a crank 243 mounted on the crank operated sprocket 242 turns the sprockets 233 and 241 and the nuts associated therewith in unison to move the side guide 218 inwardly or outwardly without changing the alignment of the main portion thereof with the belts 122 and 114. Similar structure (not shown in detail) makes possible inward and outward adjustment of the side guide 219.

The belt 114 carries the carton blanks under the upper brushes 37 and 38 which brush unwanted particles of paperboard from upper portions of the carton blanks and from leading edges thereof. The lower brushes 39 and 41 brush unwanted particles of paperboard from undersides of the carton blanks and from trailing edges thereof.

UPPER AND LOWER BRUSH ASSEMBLIES

The lower brush 39 includes sections 39a and 39b (FIG. 35) which are mounted on a shaft 246 on opposite sides of the belt 114. The lower brush 41 similarly includes sections 41a and 41b mounted on a shaft 247 on opposite sides of the belt 114. The shaft 246 is rotatably mounted in bearings 248 and 248' mounted on brackets 249 and 249', respectively. The shaft 247 is rotatably mounted in bearings 251 and 251' mounted on the brackets 249 and 249', respectively. The brackets 249 and 249' are mounted on the frame members 74 and 74'. A pulley 252 mounted on the shaft 246 is driven by a belt 253 which in turn is driven by a pulley 254 carried by a shaft 255

driven by a motor 256 (not shown in detail), which is mounted on the frame of the machine. A belt 257 which runs on pulleys 258 and 259 mounted on the shafts 247 and 246, respectively, causes the brushes 39 and 41 to turn in unison. The bristles of the brushes can be mounted in a spiral fashion, and the spiral of the brush 39 can be of opposite hand to the spiral of the brush 41.

The carton blanks are held down against the upper course of the belt 114 while passing over the lower brushes 39 and 41 and under the upper brushes 37 and 38 by an arrangement of spring pressed hold-down rollers 261 (FIG. 29) mounted on a lengthwise bar frame 2611. The bar frame 2611 is supported by upright hanger rods 2612 and 2613, which are pivotally connected to end portions of the bar frame 2611. The hanger rod 2612 is supported on a transverse bar 2614 which is supported on uprights 2616 and 2617 (FIG. 30) mounted on the frames 76 and 76', respectively, of the machine. The hanger rod 2612 is threaded, and nuts 2618 and 2629 (FIG. 29) threaded on the hanger rod 2612 hold the hanger rod 2612 in firm upwardly and downwardly adjustable position. The hanger rod 2613 is supported from a transverse bar 2620 which is supported on the elevated frames 181-182 and 207-208. Nuts 2621 and 2622 (FIG. 29) threaded thereon permit adjustment of the height of support of the right hand end of the bar frame 2611.

Each of the hold-down rollers 261 includes a facing 2626 (FIG. 36) of resilient material, such as polyvinyl chloride, and a rigid body 2627 which supports the resilient facing and is rotatably mounted on a cross shaft 2628. The facing is sufficiently resilient and deformable that the carton blanks can pass beneath it without being deformed. The cross shaft 2628 is supported in bifurcations 2629 and 2630 (FIG. 30) of a body 2631. The body carries a cross shaft 2632 which is pivotally supported by a bracket 2633 (FIG. 36). The bracket 2633 is carried by a stud 2634 mounted in the frame bar 2611. A nut 264 threaded on the stud 2634 engages the frame bar 2611 and locks the stud 2634 in position therein. A guide bolt 2641 is mounted in the body 2631 and extends upwardly through an upright bore 2648 in the frame bar 2611. The guide bolt 2641 supports a compression spring 2649 which bears on a shoulder 2651 at the upper end of a counterbore 2652 and on a nut 2653 which is threaded on the guide bolt 2641 and engages the body 2631. The spring 2649 urges the body counter-clockwise so that the roller 261 is resiliently urged toward the belt 114, but the roller 261 can move upwardly to permit carton blanks to pass thereunder. In FIGS. 5 and 29, the assembly of the bar frame 2611 and the rollers 261 is shown in a raised position in full lines. When the machine is in use, the assembly is lowered to the position at which rollers are shown in dashed lines at 261a where the rollers can hold carton blanks against the belt 114.

Details of construction of the upper brushes 37 and 38 and supports therefor are shown in FIGS. 29 and 30. As shown in FIG. 30, the brush 37 includes bristle sections 37a and 37b mounted on a shaft 266 on opposite sides of the bar frame 2611. Similarly, the brush 38 includes bristle sections 38a and 38b mounted on a shaft 267 on opposite sides of the bar frame 2611. The shaft 266 is rotatably mounted in bearings 2671 and 2672 mounted on swinging frame plates 2673 and 2674, respectively, details of the frame plate 2673 being shown in FIG. 29. The shaft 267 is rotatably mounted in bearings 2676 and 2677 (FIG. 30) mounted on the swinging frame plates 2673 and 2674, respectively. The swinging frame plates 2673 and 2674 are carried by upright plates 2678 and 2679, respectively, which form part of an overhead framework 2681. Details of construction of the upright plate 2678 are shown in FIG. 29, the upright plate 2679 being of similar construction. The overhead framework 2681 is supported by upright frames 2682 (FIG. 29) and 2683 supported on the frames 74 and 74' respectively. The overhead framework 2681 is pivotally supported on the upright frames 2682 and 2683 on aligned pivot pins, one of which is shown at 2684. Cantilever support frames 2686 and 2687 (FIG. 30) are mounted on the upright plates

2678 and 2679, respectively, and extend over the transverse bar 2614. Adjustment screws 2689 and 2691 threadably mounted in the cantilever support frames 2686 and 2687 and bearing on the transverse bar 2614 support the elevated framework with the upper brushes 37 and 38 in position to engage and brush carton blanks supported on the upper course of the belt 114 and held down by the rollers 261. A motor 271 mounted on the elevated framework 2681 drives a belt 272 which runs on a pulley 273 mounted on the shaft 266 to drive the upper brushes. A belt 274 which runs on pulleys 276 and 277 mounted on the shafts 267 and 266, respectively, causes the shafts 267 and 266 to turn in unison. Bristles of the brushes 38 and 37 can be spirally wound with the spiral of the bristles of the brush 37 being of opposite hand to the spiral of the bristles of the brush 38.

Hollow hoods 2771 can be mounted above the upper brushes 27 and 38 as shown in FIGS. 6 and 29. Suction line (not shown) can be connected to side arms 2772 which communicate with the interiors of the hoods 2771 to withdraw bits of paperboard brushed from the carton blanks. A suction hood (not shown) can be mounted below the lower brushes 39 and 41, if desired, to collect bits of paperboard brushed from the carton blanks by the lower brushes 39 and 41, or the particles can be allowed to fall from the brushes by action of gravity.

As each carton blank passes above the idle roll 2162 (FIG. 29) and beyond the last of the hold-down rolls, indicated at 261', the carton blank is projected substantially horizontally as shown at 33a to between the elevating belts 42 and 43 and is caught therebetween and swung to the position 33b at which the trailing edge portion of the carton blank swings into engagement with the lower brush 44. The lower brush 44 is carried by a shaft 2770 rotatably mounted in bearings 2773 and 2774 (FIG. 35) carried by frames 2776 and 2777, respectively, mounted on the main frames 76 and 76'. A sprocket 2778 carried by the shaft 2770 is driven by a chain 2779 (FIG. 5) which runs on a sprocket 2780 carried by a shaft 2781 of a motor 2782. A hollow suction hood 2783 (FIG. 35) is mounted below the lower brush 44 to receive bits of paperboard brushed from the carton blanks thereby. A source of vacuum (not shown) can be connected to a side arm 2785 which communicates with the interior of the hood 2783 for withdrawing the bits of paperboard.

The lower elevating belt 43 (FIG. 5) runs on a roller 2787 mounted on the drive shaft 132 and on idle rolls 2788, 2789, 2791, and 2792. The idle roll 2791 is mounted adjacent and above the lower brush 44 on a shaft 2793 (FIG. 29) carried by upright frames 2794 (FIG. 5), only one of which is shown, mounted on the framework of the machine. The idle rolls 2788 and 2789 are rotatably mounted on shafts carried by pivotably mounted frames 2796, only one of which is shown, which swing on a pivot 2797 carried by frame elements 2798. An adjusting screw 2799 threaded in a frame 2801 engages one of the pivotably mounted frames 2796 to swing the frames 2796 for tightening the belt 43. The roll 2792 is rotatably mounted on a shaft 2803 carried by plates 2804, only one of which is shown, mounted on the frame of the machine. The upper elevating belt 42 runs on a roll 2806 carried by the drive shaft 133, on a series of idle rolls 2807 carried between frame plates 2808 and 2809 (FIG. 30), an idle roll 2811 carried by a shaft 2812 rotatably mounted in bearings 2813 and 2814 carried by swinging frames 2816 and 2817, respectively, and around an adjustable idle roll 2818 (FIG. 5). The swinging frames 2816 and 2817 are swingably mounted on a cross shaft 2821 carried by the frame plates 79 and 79'. Cantilever frames 2823 and 2824 (FIG. 30) are attached to the swinging frames 2816 and 2817, respectively, and extend over the transverse bar 2614. Adjustment screws 2826 and 2827 threaded in the cantilever frames 2823 and 2824, respectively, bear on the transverse bar 2614 to adjust the position of the swinging frames 2816 and 2817 and the roller 2811.

The frame plates 2808 and 2809 are welded to cross bars 2831 and 2832 (FIG. 5) which are attached to the swinging

frames 2816 and 2817 so that the swinging frames 2816 and 2817, the frame plates 2808 and 2809 and the rolls 2807 and 2811 swing up and down as a unit. Portions 283 and 284 (FIG. 29) of the belts 43 and 42, respectively, move to the left as shown in FIG. 29 and serve to catch the carton blanks as the carton blanks are projected between the portions 283 and 284. The belt courses advance upwardly and to the left therefrom in face-to-face relation being guided by the rolls 2807, and each carton blank after being projected substantially horizontally from the belt 114 is swung clockwise as it is caught by and advances with the elevating belts 43 and 42 so that the trailing edge of each carton blank is swung into engagement with the lower brush 44 as the carton blank starts upwardly with the elevating belts 43 and 42. The lower brush 44 rotates in a clockwise direction as shown in FIG. 29 to draw remaining bits of paperboard from each carton blank.

SIDE BRUSH ASSEMBLIES

20 The elevating belts 42 and 43 carry the carton blanks between the side brushes 46 (FIG. 6) and 46' (FIGS. 5 and 6), which brush unwanted particles of paperboard from side edges of the carton blanks. Supports for the side brushes 46 and 46' are similar, and only the supports for the side brush 46' will be described in detail. The side brush 46' is mounted on a shaft 309 (FIG. 17) of an electric motor 311. The motor 311 is mounted on a platform 312 which has downwardly extending legs 313 and 314. Adjustment screws 316 and 317 are received in sockets 318 and 319, respectively, in the legs 313 and 314, respectively. Lower ends of the adjustment screws 316 and 317 are received in sockets 321 and 322 (FIG. 18), respectively, in blocks 323 and 324. The blocks 323 and 324 are linked by a horizontal plate 326 (FIGS. 16 and 18) attached thereto by fasteners 327. The blocks 323 and 324 are provided with horizontal bores 328 and 329 (FIG. 18), respectively, which receive transverse rods 331 and 332, respectively. The rods 331 and 332 are mounted in a bearing block 333 (FIGS. 16 and 17) which is mounted on the frame 76 by means of fasteners 334 mounted in bores in the frame 76 and received in a slot 336 (FIG. 17) in the bearing block 333. The rods 331 and 332 are also mounted in an opposed bearing block 337 (FIG. 6) associated with the brush 46 and mounted on frame 76'. The blocks 323 and 324 are movable to the left or right, as shown in FIG. 16, along the rods 331 and 332. A threaded shaft 339 rotatably mounted in the bearing block 33 is threaded in a horizontal opening 341 (FIG. 18) in a block 342 attached to the plate 326 by fasteners 342. Turning of a handwheel 343 (FIGS. 16 and 17) mounted on the threaded shaft 339 advances the blocks 323 and 324 to the right or left as shown in FIG. 16. Opposite portions of the adjustment screws 316 and 317 are provided with threads of opposite hand so that turning of the adjustment screws 316 and 317 causes raising or lowering of the motor 311 and of the brush 46'. By means of the hand-wheel 343 and of the adjustment screws 316 and 317, the height and position of the brush 46' with respect to carton blanks 33 carried by the belts 42 and 43 can be adjusted as shown most clearly in FIG. 16. The carton blanks and bristles of the side brush overlap as shown in FIG. 16 with the carton blanks passing at an angle of approximately 50° to a horizontal plane through the axis of the brush 46', as shown in FIG. 17. A hood 344 (FIGS. 16 and 17) surrounds the portion of the brush 46' which does not engage the carton blanks. The hood can be mounted on the casing of the motor 311. A side arm 346 attached to the hood can be connected to a source of suction (not shown in detail) so that pieces of paperboard brushed from the carton blanks can be collected and disposed of.

COUNTER MECHANISM

From the side brushes 46 and 46' (FIG. 6) the carton blanks advance upwardly between the elevating belts 42 and 43 to be transferred to a pair of spaced upper counter belts 348 and 349 and a pair of spaced lower counter belts, one of which is

indicated at 351 in FIG. 5, the other of which is shown at 351' in FIG. 20, and which are aligned with the upper counter belts 348 and 349. The upper counter belts 348 and 349 run on a roller 352 which is carried by the power driven shaft 134, around an idle roll 353 (FIG. 5) having a shaft 354 supported by an adjustable mount, and an idle roll 357 over idle rolls 361 and 362 which also support the lower counter belts, and a pair of spaced counter rolls 363 and 364 (FIG. 20) and around spaced adjustable rolls 366 and 367 which are mounted on a shaft 368. The lower counter belts run on the spaced counter rolls 363 and 364, around an idle roll 370 (FIG. 5) having a shaft provided with adjustable supports, around a roller 373 supported on the driven shaft 136, around an idle roll 276 and over the rolls 361 and 362. Appropriate belt guides 377 and 377' can be provided to keep the belts in alignment.

The shaft 368, which supports the spaced adjustable rolls 366 and 367, is journaled in bearings 378 and 379 (FIG. 20) mounted in a swinging framework 381. The swinging framework 381 includes lengthwise members 382 and 383 which are pivotally mounted on a cross shaft 384. The cross shaft 384 is mounted in openings 386 in plates 387 (only one of which is shown in detail) attached to the frame plates 79 and the opposed frame plate 79'. Upright adjustment screws 388 (only one of which is shown) support a cross rod 389 which extends through openings 391 and 392 in the lengthwise members 382 and 383, respectively. The upright adjustment screw 388 is threaded in an upright bore in an extension arm 393 of the plate 387.

The lengthwise members 382 and 383 are connected together by a cross bar 394 on which a back-up flange 396 is mounted. A bolt 397 extends through a slot 398 in the back-up flange and is mounted in a cross bar 399 which is pivotally mounted in arms 400 and 401 which are pivotally mounted on the cross shaft 384. The arms 400 and 401 support a transverse rod 402 on which a roller 403 is rotatably mounted in position between upper and lower pairs of counter belts. A compression spring 404 (FIG. 19) mounted on the shank of the bolt 397 urges the cross bar 399, the arms 400 and 401, the roller shaft 402, and the roller 403 downwardly as shown in FIG. 19. The roller 403 can engage carton blanks traveling between upper and lower pairs of counter belts to hold the central portions of the carton blanks against a switch housing 405 of the counter switch 47. A head 405' on the bolt 397 is engageable with the flange 396 to prevent excessive dropping of the roller 403. For clarity, the roller 403 is shown in a raised position in full lines in FIG. 19. When in use, the roller is urged downwardly to the dot-dash lines position indicated at 403'. A push button 406 mounted in the housing 404 is engaged by each carton blank as it travels upwardly with the counter belts and around the spaced rolls 363 and 364. As the trailing edge of each carton blank passes the push button 406, the push button is released to close switch contacts inside the housing 405. The switch housing 405 is mounted on a plate 408 which carries elongated mounting bolts 409 and 411. The bolts 409 and 411 extend through openings in plates 412 and 413 mounted on opposite sides of a short frame bar 414 and through an elongated slot 415 in the frame bar 414. End portions of the frame bar 414 are mounted on cross bars 417 and 418 attached thereto by appropriate fasteners 419 and 421, respectively. Adjustment nuts 422 and 423 on the bolt 409 and 424 and 426 on the bolt 411 make possible upward and downward adjustment of the position of the switch housing as well as adjustment lengthwise of the short frame bar 414.

STACKING AND ELEVATOR ASSEMBLIES

From the switch housing 405, the carton blanks pass onto a conveyor belt 422' (FIG. 7) which runs on an idle roll 427 and on a roll 428 mounted on the driven shaft 100. Appropriate upper side guides 429 and 4291 (FIG. 34) are provided on opposite sides of the belt 422' for realigning the carton blanks if necessary. As shown in FIG. 33, brackets 4292 and 4293 are mounted on the side guide 4291, each of which is carried by

swinging brackets 4294 and 4295, respectively. As shown in FIG. 21, the swinging bracket 4295 is carried by a threaded rod 4296 which is received in a nut 4297. The nut 4297 is rotatably mounted in a frame bracket 4298 and carries a sprocket 4299. Turning of the sprocket 4299 advances one end portion of the side guide 4293 inward or outward. A chain 430 (FIG. 7) running on the sprocket 4299 and on another sprocket 4301 associated with a threaded rod 4302 causes both end portions of the side guide to advance inwardly and outwardly together in the manner already described in connection with the other side guides, when a crank 4303 is turned to turn a sprocket 4304 attached thereto which drives the chain 430. The upper side guide 429 can be provided with similar mechanism for inward and outward advance thereof. The conveyor belt 422' advances the carton blanks to a plurality of lower nip rolls 431 and 432 (FIG. 21) and upper nip rolls 436 and 437. The lower nip rolls are mounted on the power driven shaft 99. The upper nip rolls are mounted on a cross shaft 439 which is rotatably mounted on swinging frames 441 and 442. A belt 443 runs on pulleys 444 and 446 mounted on the cross shaft 439 and on the driven cross shaft 101 to drive the cross shaft 439 and the upper nip rolls, the upper and lower nip rolls turning in opposite directions. The nip rolls engage each carton blank and project the carton blank into engagement with downwardly hanging valve actuator arms 48 from which the carton blank falls onto horizontal elevator bars 448 (FIGS. 7, 8 and 9) 449, 450 and 450' (FIGS. 9 and 22) where the carton blanks are accumulated in a stack 451 (FIG. 7). As the carton blanks accumulate in the stack 451, a hanging patter plate 452 swings back and forth so that one side of the patter plate 452 engages the carton blanks in the stack to straighten the stack with the uppermost carton blank being normally engaged by inclined lower portions 447' of the arms 453 and 454. The patter plate 452 is supported by upright brackets 453 and 454 (FIG. 21) attached to a side thereof opposite the side which engages the carton blanks of the stack 451. The brackets 453 and 454 are supported by bearings 456 and 457, respectively, mounted on the shaft 99. A cam 458 mounted on the shaft 100 drives the patter plate. The cam 458 is engaged by a cam follower 459 mounted on a crank arm 460 which is carried by a sleeve 461. The sleeve 461 is pivotally mounted on a stationary cross rod 463 attached to the side frames 77 and 77'. Cranks 464 and 466 are also mounted on the sleeve 461. Adjustable links 467 (one of which is shown in FIG. 7) connect the cranks 464' and 466 with the brackets 453 and 454 (FIG. 21). A compression spring 468 mounted on an eyebolt 469 connected to the cam follower crank 460 and bearing on bracket 469' attached to the frame 77 holds the cam follower 459 in engagement with the cam 458. As the cam 458 turns, the patter plate 452 is rocked back and forth about the bearings 456 and 457 to pat the carton blanks into a smooth stack.

The valve actuator arms 48 are part of a swinging assembly 447, which is pivotally mounted on a pivot pin 4571 (FIG. 7). The pin 4571 is supported in side frames 4572 and 4572' (FIG. 31) which are carried by a horizontal plate 4572''. The plate 4572 is adjustably mounted on a block 4572''' (FIG. 32) which is carried by a cross frame 4573. The cross frame 4573 is mounted on sliding brackets 4574 (FIGS. 7 and 31) and 4574' (FIG. 31). The brackets 4574 and 4574' are slidably mounted on lengthwise rods 4576 and 4576', respectively, only one of which is shown in detail, mounted on the main framework of the machine. A clamp bracket 4576'' is fixedly clamped on the rod 4576. A stud 4576''' is mounted on the bracket 4576'' and extends through a bore 4576a in a flange 4576b of the sliding bracket 4574. Nuts 4576c and 4576d on the stud 4576''' can be turned for adjustably moving the bracket 4574 lengthwise of the machine. Similar structure, not shown, associated with the sliding bracket 4574' makes possible lengthwise adjustment thereof together with the other end of the frame 4573.

A link 4577 is pivotally connected to a block 4577' (FIGS. 7 and 32), which is a part of the assembly 447, and to a crank

4578. The crank 4578 actuates valve mechanism inside a valve housing 4579. A compression spring 4580 urges the valve actuator arms 48 to the right (counterclockwise) as shown in FIG. 7. Appropriate stops 4581 (FIG. 31) and 4582 (FIG. 32) threaded in an upright bar 4583, which is a part of the swinging assembly 447, limit the amplitude of swinging of the assembly 447. The stop 4581 (FIG. 31) is engageable with a stationary cross frame 4584. The stop 4582 (FIG. 32) is engageable with the plate 4572''. The valve in the housing 4578 controls flow of hydraulic fluid to elevator raising and lowering mechanisms during delivery of carton blanks thereto, as will be explained in greater detail hereinafter.

The horizontal elevator bar 448, and similar elevator bars 449, 450 and 450' (FIGS. 9 and 22) are mounted on a cross bar 471 which forms a part of a sliding frame 470 carried by an upright plate 472 (FIGS. 22 and 23) which is attached to sliding blocks 473 and 474. The blocks 473 and 474 are slideably mounted on upright bars 476 and 477 (FIG. 23) respectively, which are mounted on a lower cross frame 478 (FIG. 22) and an upper cross frame 479 (FIGS. 8 and 9). A pivot pin 481 (FIG. 23) is supported on a bracket 482 attached to the plate 472. Ends of lever arms 483 and 484 are pivotally mounted on the pivot pin 481. Opposed ends of the lever arms 483 and 484 are pivotally connected to an upper end of a link 486 (FIG. 8). The lower end of the link 486 is pivotally connected to a frame 487. A piston rod 488 is also pivotally connected to the lever arms 484 and 483. A piston (not shown) attached to the piston rod 488 moves in a cylinder 489 which is pivotally attached to a frame 491. Operation of the cylinder 489 causes swinging of the lever arms 483 and 484 to raise the elevator bars to a raised position indicated in dot-dash lines at 448' in FIG. 8 and to lower the elevator bars to a lowered position indicated in double dot-dash lines at 448''. A spring-pressed rod 491' is also pivotally connected to the lever arms 483 and 484. A compression spring 492 mounted thereon and bearing on a lug 493 mounted on a bracket 494 carried by the link 486 urges the lever arms 483 and 484 upwardly to counterbalance the weight of the lever arms, the blocks 473 and 474 and the elevator bars and also a portion of the weight of carton blanks stacked thereon.

As was indicated above, the valve mechanism in the valve housing 4579 controls flow of hydraulic fluid to the cylinder 489 during delivery of carton blanks to the valve actuator arms 48 (FIG. 7). Each time the valve actuator arms 48 are advanced clockwise as a carton blank hits them, a small amount of fluid is introduced into the upper end of the cylinder 489 to lower the elevator bars incrementally. When the carton blank falls onto the stack 451, the valve actuator arms 48 return to a centered position in engagement with the stack at which the elevator bars remain stationary. However, if the elevator bars are lowered sufficiently that the valve actuator arms can swing counterclockwise from the position shown, fluid is introduced into the lower end of the cylinder 489 to raise the elevator bars until the stack 451 engages the inclined lower portions 447' of the valve actuator arms 48 to hold them in the centered position shown.

When a stack of appropriate size and including a selected number of carton blanks has been accumulated on the elevator bars 448, 449, 450 and 450', the elevator bars are lowered to the position 448' by drawing the piston rod 488 downwardly into the cylinder 489. Then, the stack of carton blanks is pushed from the elevator bars by upright pusher bars 496 (FIG. 8), 497 (FIG. 24). The pusher bars are mounted on a plate 499 which is part of a sliding pusher frame 500 which is carried by sliding blocks 501 and 502. The blocks 501 and 502 are slideably mounted on horizontal rods 503 and 504, respectively. A piston rod 506 is pivotally attached to the plate 499. The piston rod 506 is attached to a piston (not shown) which works in a hydraulic cylinder 507. When fluid under pressure is introduced into the right hand end of the cylinder 507, as shown in FIGS. 8 and 24, the upright pusher bars 496, 497 and 498 are moved to the left to push the stack of carton blanks off

the elevator bars and onto conveyor belts 508 (FIGS. 2 and 25) and 509 (FIG. 26).

DISCHARGE CONVEYOR AND INVERTING ASSEMBLY

As shown in FIGS. 25 and 26, the conveyor belts 508 and 509 run on driven rolls 511 and 512 and on pairs of small idle rolls 513-514 and a pair of large idle rolls 516-517, all of which are rotatably mounted on a framework 518. A motor 519 (FIG. 25) drives a chain 521 which runs on a sprocket 522 (FIG. 26) which drives a shaft 523 on which the driven rolls 511 and 512 are mounted. When the stack of carton blanks reaches the position indicated at 451' in FIG. 25, the stack engages a switch operator 524 of a limit switch 526 which is part of a control circuit for the motor 519 as will be explained in greater detail hereinafter. The outer carton 56 (FIG. 1) is placed over the stack while the stack is on the conveyor belts 508 and 509. Then the motor 519 can be energized to advance the carton with the stack thereinside to the turntable 57 of a carton inverting assembly 525.

The carton inverting assembly 525 includes a stationary framework 528 (FIGS. 2, 25 and 26) on which bearings 529 and 530 (FIG. 26) are mounted. The turntable 57 is of generally U-shape and is carried by pivot pins 532 and 533 swingably mounted in the bearings 529 and 530. The turntable 57 includes a main frame member 534 of generally E-shape, as shown in FIG. 25, which includes a main transverse bar 535, an elongated central cross member 536 and short cross members 537 and 538 at opposite ends of the transverse bar 535. The pivot pins 532 and 533 are carried by radial members 539 and 540 mounted on the short cross member arms 537 and 538, respectively. A pair of roller frames 542 and 543 is mounted on the main transverse bar 535. A second pair of roller frames 544 and 546 is mounted on a cross arm 547 attached to the central cross member 536 spaced from the main transverse bar 535. Input rollers 548 are rotatably mounted on the roller frames 542 and 543. Output rollers 549 are rotatably mounted on the roller frames 544 and 546. The roller frames 544 and 546 are parallel to the roller frames 542 and 543 but are spaced therefrom and on opposite sides of the axis of the pivot pins 532 and 533. The turntable 57 swings from an input position shown in FIG. 2 and in which the input rolls are shown in FIG. 25 in dot-dash lines at 548' through the full line position of FIG. 25 to an output position at which the output rolls are indicated at 549'' in double dot-dash lines in FIG. 25. When the swinging frame 57 is in the input position, a switch actuator 551 of a limit switch 552 is engaged by the input roller frame at the position 548'. When the swinging frame 57 is in the output position, a switch actuator 553 of a limit switch 554 is engaged by the output roller frame at the position 549''. When the swinging frame 57 is in the input position, as shown in FIG. 1, the outer carton 56 and the stack of carton blanks can roll onto the input rollers 548 (FIG. 25). When the outer carton is on the input rollers, it engages a switch actuator 556 of a limit switch 557. The swinging frame 57 then is swung through the full line position of FIG. 25 at which the outer carton can rest on the cross member 536 to the output position (double dot-dash line position of FIG. 25). In the output position, the outer carton is inverted to upright position ready for closing and rests on a switch actuator 558 of a limit switch 559. The outer carton and the stack of carton blanks thereinside can then roll off the output rollers onto the delivery conveyor 58 (FIG. 1), not shown in detail, where the outer carton can be closed and sealed. The swinging frame or turntable 57 is caused to swing by a motor 562 which drives gearing (not shown in detail) in a gear box 563 to a drive shaft 564 on which a sprocket 566 is mounted. The sprocket 566 drives a chain 567 which runs on a sprocket 568 mounted on the pivot pin 533. The motor 562 is provided with a first winding 5621 (FIG. 27) which drives the motor in a direction to swing the turntable 57 in a counter-clockwise direction as shown in FIG. 25, and a second winding 5622 (FIG. 27) which drives the motor in a direction to swing the turntable 57 clockwise as shown in FIG. 25.

OPERATION

The operation of the machine will be explained with reference to FIG. 27, which shows electrical connections of the machine, and FIG. 28, which shows hydraulic connections.

Electric power is supplied by positive power leads 585 and 586 and a negative power lead 587. Operation of the machine is initiated by closing push button switches 588 and 589 to energize a coil of a relay 591. Closing of contacts 592-593 of the relay 591 connects the positive power lead 585 to a positive lead 594. Closing of contacts 596-597 of the relay 591 connects the negative power lead 587 to a negative lead 598. Closing of contacts 599-601 of the relay 591 connects the positive power lead 586 to a positive lead 602. The lead 602 is connected to one side of a rectifier network 6021. The opposite side of the rectifier network 6021 is connected to the negative lead 598 so that rectified direct current is provided across leads 6022 and 6023 of the rectifier network 6021. A hold-in circuit for the relay 591 is provided from the positive lead 594 through contacts of a normally closed push button switch 603, a lead 604, the coil of the relay 591, and a lead 606 to the negative lead 598. Opening of the switch 603 releases the hold-in circuit to permit the contacts of the relay 591 to open. A lamp 607 mounted in parallel with the coil of the relay 591 indicates when the relay coil 591 is energized. When the relay 591 is energized, power is supplied to the main drive motor 81 through leads 608 and 609 connected to the positive lead 594 and to the negative lead 598, respectively.

Hydraulic pressure is supplied by a pump 611 (FIG. 28) which draws hydraulic liquid 612 from a reservoir 613 and supplies liquid under pressure to a pressure line 614. A pressure relief valve 616 permits return of fluid to the reservoir 613 through an exhaust line 617.

The pressure line 614 supplies fluid under pressure to a valve 618 which controls the supply of fluid under pressure to the pusher cylinder 507. When the pusher cylinder is not operating, the valve 618 is normally in the position shown at which pressure is introduced into the left hand end of the cylinder 507 to urge the pusher bars to retracted position. When the pusher bars are in retracted position, contacts of a limit switch 620 (FIG. 27) are closed to energize a solenoid 621 of a valve 622 through a circuit from the positive lead 594 through the contacts of the limit switch 620, a lead 623, normally closed contacts 624-626 of a relay 627 and the solenoid coil 621 to the negative lead 598. As shown in FIG. 28, when the solenoid 621 is energized, the valve 622 is advanced to a position in which pressure is supplied to a line 628 which serves a quick index valve 629. The valve 629 is normally in the position shown at which the pressure is supplied to the valve 4579 through a line 631. When no carton blanks are on the elevator bars, the valve 4579 swings counter clockwise from the position shown sufficiently to permit pressure from the line 631 to pass through the valve 4579, a line 632 and a pressure controlled check valve 633 to the lower end of the elevator cylinder 489 to cause the piston rod 488 thereof to be raised to raise the elevator bars until the sliding frame 470 on which the elevator bars are mounted is raised to the position at which it engages the operator of a limit switch 634 (FIG. 27) to open contacts 636-637 thereof and to close contacts 638-639 thereof. Closing of the contacts 638-639 energizes the coil of a relay 641 through a circuit from the positive power lead 585 through the contacts 638-639, a lead 642, contacts 643-644 of a reject switch 646, a lead 647, and the coil of the relay 641 to the negative power lead 587. Energizing of the relay 641 causes opening of the contacts 649-651 thereof which are connected to reset leads 652 and 653, respectively, of a counter mechanism 654 (not shown in detail). Opening of the circuit between the counter reset leads 652 and 653 permits the counter mechanism to return to a zero reading ready for the start of a count. Contacts 654-655 of the relay 641 also open to open the circuit to an alarm 656. Contacts 657-658 of the relay 641 close when the relay 641 is energized to provide a hold-in circuit for the relay 641 from

the positive power lead 585 through normally closed contacts 659-661 of a limit switch 662, a lead 663', the contacts 657-658 of the relay 641, a lead 664, the contacts 643 and 644 of the reject switch 646, a lead 647, and the coil of the relay 641 to the negative power lead 587.

At this point, the motor 165' is energized to drive the feed table belt 32 (FIG. 1) by means of a circuit (FIG. 27) from the positive lead 594 through normally closed contacts 661'-662' of a relay 663, a lead 664', and the motor 165' to the negative lead 598 so that the feed table delivers carton blanks to the belt 122 (FIG. 3). In addition, at this point, the clutch 90 is caused to engage by a circuit from the lead 6022 through normally closed contacts 666-667 of the relay 663, a lead 6671, and a coil of a clutch actuating solenoid 668 to the lead 6023 so that the belts 122 and 114 (FIG. 3) operate to draw the carton blanks under the discriminator 34 and between the upper brushes 37 and 38 and the lower brushes 39 and 41, the elevating belts 298 and 299 operate to swing the carton blanks against the bottom brush 44, and the counter belts 348, 349, 351 and 351' carry the carton blanks past the counter button 406. The belt 422 (FIG. 7) and the nip rolls operate continuously as long as the motor 81 operates to carry the carton blanks forward and to project each carton blank in turn against the valve actuating plate 447.

As each carton blank passes the counter button 406, the button 406 is depressed and then released as the trailing edge of the carton blank passes beyond the button 406. The counter switch 47 (FIG. 27) is opened and then closed to operate the counter 654 as each carton blank passes the button 406. As each carton blank is projected against the valve actuating arms 48, the valve 4579 (FIG. 28) swings clockwise to permit pressure from the line 631 to pass through a line 672 to the upper end of the cylinder 489 to cause incremental lowering of the piston rod 488 and the elevator sliding frame 470, pressure from the line 672 operating through a pilot line 673 to open the pilot check valve 633 when there is increased pressure in the line 672 to permit exhaust from the lower end 40 of the cylinder 489 through the line 632 and the valve 4579 to an exhaust line 676. As already pointed out, after each carton blank has been projected against the valve actuating arms 48, the assembly 447 swings back to the centered position shown with the inclined lower portions 447' of the valve actuating arms 48 engaging the uppermost of the carton blanks stacked on the elevator bars. If the elevator bars become too far lowered, the valve can swing counter clockwise to permit pressure from the line 631 to be introduced through the valve 4579, the line 632 and the pilot check valve 633 to the lower end of the cylinder 489 to raise the elevator bars until the inclined lower portions 447' of the valve actuating arms 48 rest against the uppermost of the carton blanks on the stack while the valve 4579 is centered. The patter plate 452 (FIGS. 7 and 21) is arranged to maintain the stack in proper position for engagement by the lower inclined portions 447' (FIG. 7) of the valve actuator arms 48.

As the elevator sliding frame 470 advances downwardly, it reaches a position where it engages the actuator of a limit switch 681 (FIG. 27) to close the contacts thereof. The limit switch 681 is positioned to be closed when the stack is of proper height to include a selected number or count of carton blanks. Closing of the contacts of the limit switch 681 connects a lead 682 from a counter operated switch 683 to a lead 684. When the counter 654 reaches the selected count, contacts of the switch 683 close to connect the lead 682 to the positive lead 594. Power for operating the counter 654 is supplied by the power leads 585 and 587. When the contacts of the counter switch 683 close while the limit switch 681 is closed, the lead 684 is connected to the positive lead 594 to energize the lead 684. Energizing of the lead 684 energizes the relay 663 and also energizes a time delay relay 685 and a solenoid 686 which actuates the quick index valve 629, the relays 663 and 685 and the solenoid 686 being connected to the negative lead 598.

When the solenoid 686 is energized, the valve 629 (FIG. 28) moves to its other position at which the line 628 is connected directly to the line 672 by-passing the valve 4579, and the elevator advances rapidly downwardly until the sliding frame 470 thereof engages the actuator of a limit switch 690 to close the contacts thereof. In the event the counter switch fails to operate properly and a stack builds up which is higher than is desired and larger than a stack having the selected count, the sliding frame 470 descends into engagement with the limit switch 662 to close contacts 691-6911 thereof and open the contacts 659-661 thereof. Closing of the contacts 691-6911 energizes the relays 663 and 685 and the solenoid 686 to cause rapid descent of the elevator in the same manner as if the counter switch 683 had operated properly. Opening of the normally closed contacts 659-661 of the limit switch 662 as the elevator sliding frame 470 passes the limit switch 662 after the counter switch 683 has operated properly has no effect because the normally closed contacts 659-661 are mounted in parallel with normally open contacts 693-6931 of the relay 663 which close upon proper operation of the counter switch 683. However, if the counter switch 683 fails to operate properly, opening of the normally closed contacts 659-661 of the limit switch 662 de-energizes the coil of the relay 641 to permit the relay 641 to return to its normal position to energize the alarm 656. The alarm 656 is energized by a circuit from the power lead 585 through the contacts 654-655, a line 6932, and the alarm 656 to the power lead 587.

Energizing of the relay 663 causes opening of the normally closed contacts 661'-662' thereof to de-energize the motor 165' causing stopping of the feed table 31. In addition, opening of normally closed contacts 666-667 thereof de-energizes the clutch actuating solenoid 668 to release the clutch 90 and stop advance of the belts 114 and 122, the elevating belts 298 and 299 and the counter belts 348, 349, 351 and 351'. Closing of normally open contacts 694-696 of the relay 663 causes energizing of a solenoid 697 which operates a brake 698 for stopping a clutch driven shaft 699 through a circuit from the lead 6022 through the contacts 694-696, a lead 701, and the coil of the solenoid 697 to the lead 6023. Closing of normally open contacts 702-703 of the relay 663 connects the positive lead 594 to a lead 704. A hold-in circuit for the relays 663 and 685 and the solenoid 686 is provided from the lead 704 through the normally closed contacts 636-637 of the limit switch 634 and the lead 684 so that the relays 663 and 685 and the solenoid 686 remain energized until the contacts 636-637 of the limit switch 634 open as the elevator sliding frame 470 reaches its uppermost position at the start of a new cycle. The belt 422 (FIG. 7) and the nip rolls continue to move after the clutch 90 has been de-energized to add such carton blanks as have passed the counter button to the stack on the elevator bars. Contacts of the time delay relay 685 close a short time after the relay 663 is energized to connect a solenoid 751 of a by-pass valve 748 between the positive lead 594 and the negative lead 598 to energize the solenoid 751 and move the valve 748 from the position shown to its other position.

When the contacts of the limit switch 690 are closed as the elevator sliding frame 470 reaches its lowermost position, a circuit is provided to a solenoid 708 of the valve 618 from the positive lead 594 through the normally closed contacts 692-6921 of the relay 627, a lead 709, the contacts of the limit switch 690, a lead 711, normally closed contacts 712-713 of the limit switch 526, a lead 714, and the coil of the solenoid 708 to the negative lead 598. Energizing of the solenoid 708 causes moving of the valve 618 to its other position. When the valve 618 is in its other position (FIG. 28) pressure from the line 614 is directed along a line 716 to the right hand end of the pusher cylinder 507 to cause the pusher bars to move to the left as shown in FIGS. 2 and 24 to advance the stack of carton blanks off the elevator bars and onto the discharge conveyor belts 508-509. As the stack is being advanced onto the discharge conveyor belts, upper courses of the belts advance in a leftward direction to carry the stack

onto the discharge conveyor, the belts being driven by the motor 519 (FIG. 27) which is energized by a circuit from the positive lead 594 through normally closed contacts 718-719 of the limit switch 526, a lead 721 and the motor 519 to the negative lead 598. When the stack has been advanced onto the discharge conveyor sufficiently to engage the switch actuator 524 of the limit switch 526, the normally closed pairs of switch contacts 712-713 and 718-719 of the switch 526 are opened. The pusher bars continue advancing until the sliding pusher frame 500 engages the actuator of a limit switch 720 to close the contacts thereof.

Opening of the pair of contacts 712-713 de-energizes the solenoid 708, but the valve 618 remains in its other position at this time. Opening of the pair of contacts 718-719 de-energizes the discharge conveyor motor 519 to stop the discharge conveyor. While the discharge conveyor is stopped with the stack of carton blanks thereon, the outer carton 56 (FIG. 1) is mounted on the stack, as already described. Then a foot switch 7211 (FIG. 27), which is in parallel with the contacts 718-719, is closed to again energize the motor 519 to start up the discharge conveyor again, and the assembly of the stack of carton blanks and the outer carton is advanced onto the rolls 548 of the turntable 57. When the assembly has been advanced onto the rolls 548 sufficiently to engage the switch actuator 556 of the limit switch 557 (FIG. 27), normally open contacts 723-724 thereof close and normally closed contacts 726-727 thereof open. Closing of the contacts 723-724 completes a circuit to the forward winding 5621 of the turntable motor from the positive lead 594 through the contacts 723-724, a lead 728, normally closed contacts of the limit switch 554, a lead 730, and the forward winding 5621 to the negative lead 598 causing the turntable to turn approximately 180 degrees to the double dot-dash line position of FIG. 25 at which the assembly of outer carton and stock of carbon blanks rests on the switch actuator 558 of the limit switch 559 to open the contacts thereof and the frame 544 engages the switch actuator 553 of the limit switch 554 to open the contacts thereof. The outer carton or case 56 is sufficiently deep that it holds the limit switch 557 in position with contacts 723-724 closed throughout the turning thereof. Opening of the contacts of the limit switch 554 de-energizes the forward winding 5621 to stop the swinging of the turntable 57. As shown in FIG. 25, the rolls at the position 549" slope downwardly and to the left so that the assembly rolls off the turntable to the left as shown in FIG. 25 and onto the delivery conveyor 58 (FIG. 1) with the outer carton being in inverted position ready for sealing. When the assembly has rolled off the rolls 549, the switch actuator 558 of the limit switch 559 is released and the switch 559 returns to its normal position at which the contacts thereof are closed to energize the reverse winding 5622 (FIG. 27) of the turntable motor through a circuit from the positive lead 594 through the contacts 726-727 of the limit switch 557, a lead 731, the contacts of the limit switch 552, a lead 7311, the contacts of the limit switch 559, a lead 732, and the reverse winding 5622 to the negative lead 598, and the turntable returns to its original position ready to receive the next assembly of outer carton and stack of carton blanks.

When the contacts of the limit switch 720 close as the pusher frame 500 reaches the limit of its leftward movement as shown in FIG. 27, a circuit is completed to energize the relay 627 and a solenoid 736 of the valve 618 through a circuit from the positive lead 594 through the contacts 702-703 of the relay 663, the lead 704, the contacts of the limit switch 720, and a lead 737 to the coil of the relay 627 and to the solenoid 736. The solenoid 736 and the coil of the relay 627 are also connected to the negative lead 598. Energizing of the solenoid 736 returns the valve 618 (FIG. 28) to the position shown at which pressure from the line 614 is directed through the line 716 to the left hand end of the pusher cylinder 507 to cause the pusher to be returned to the right. Energizing of the coil of the relay 627 (FIG. 27) causes opening of the contacts 624-626 and 692-6921 and closing of normally open contacts 738-739 and 741-742 thereof.

Opening of the contacts 692-6921 prevents energizing of the solenoid 708 of the valve 618 as long as the relay 627 is energized. Opening of the contacts 624-626 prevents energizing of the solenoid 621 of the valve 622 while the relay 627 is energized. Closing of the contacts 738-739 provides a hold-in circuit for the relay 627 from the power lead 594 through normally open contacts 702-703 of the relay 663, the lead 704, the contacts 738-739, and the coil of the relay 627 to the negative lead 598. Closing of the contacts 741-742 makes possible energizing of a solenoid 744 of the valve 622 when the contacts of the limit switch 620 are closed. The contacts of the limit switch 620 are closed when the sliding pusher frame 500 engages the actuator of the limit switch 620 when the pusher bars have been fully retracted. Energizing of the solenoid 744 of the valve 622 advances the valve 622 to the right as shown in FIG. 28 to connect the pressure line 614 to a line 746 which supplies the valve 748. By the time the pusher bars have been fully retracted, the time delay relay 685 operates to energize the solenoid 751 of the valve 748 to connect the line 746 with the line 632 to supply liquid to the lower end of the elevator cylinder 489 to cause rapid raising of the elevator. Liquid from the upper end of the elevator cylinder 489 is returned through the line 672, the valve 629, which is in its alternate position, the line 628 and the valve 622 to the exhaust line 617. The elevator rises until the sliding elevator frame 470 (FIG. 27) engages the actuator of the limit switch 634 to open the normally closed contacts 636-637 thereof to de-energize the relays 663 and 685 and the solenoid 686 of the valve 629. When the time delay relay 685 is de-energized, the solenoid 751 of the valve 748 is de-energized to permit the valve 748 to return to the position shown. When the solenoid 686 is de-energized, the valve 629 returns to the position shown. De-energizing of the relay 663 releases the hold-in-circuit of the relay 627 to release the relay 627, and de-energizes the solenoid 736 of the valve 618 and the brake solenoid 697. The clutch solenoid 668 is energized to start delivery of another lot of carton blanks and the cycle is repeated.

If, at the start of operation of the machine, the pusher is not fully retracted or if the elevator is not fully raised, a reset switch 755 can be closed to connect the positive lead 594 to the lead 737 for energizing the relay 627 and the solenoid 736 to cause retraction of the pusher and quick raising of the elevator. When the machine is at rest, the elevator is maintained in position by the pressure controlled check valve 633 (FIG. 28) and a check valve 756 which prevent release of liquid from the lower end of the elevator cylinder 489 when the machine is not in operation. The push button switch 646 is a reject switch. If, during a count, it is necessary to discharge a partial stack for any reason, the switch 646 can be moved to its other position at which the circuit to the relay 641 is opened to permit operation of the alarm 656 and resetting of the counter 654 and the lead 684 is energized by a circuit from the positive lead 594 through contacts 758-759 of the switch 646 to the lead 684 to energize the relays 663 and 685 and the solenoid 686 of the valve 629 to cause discharge of the partial stack.

The machine illustrated in the drawings and described above is subject to structural modification without departing from the spirit and scope of the appended claims.

Having described our invention, what we claim as new and desire to secure by letters patent is:

1. A machine for removing loose bits of paperboard from carton blanks which comprises conveyor means, means for spreading the carton blanks on the conveyor means, opposed upper and lower brush means engaging upper and lower faces of the carton blanks to brush the upper and lower faces, and side brushes engaging opposite edge portions of the carton

blanks to brush the loose bits of paperboard from the carton blanks.

2. A machine as in claim 1 wherein the conveyor means includes a belt conveyor, the upper and lower brush means include brush sections on opposite sides of the belt conveyor, and means is provided between the upper brush sections for holding the carton blanks against the belt conveyor to travel therewith.

3. A machine as in claim 2 wherein the means for holding the carton blanks against the belt conveyor includes a frame bar supported above the belt conveyor, a plurality of swinging frames pivotally mounted on the frame bar, roller means carried by each swinging frame and means for resiliently urging the swinging frames in a direction to cause the roller means to engage carton blanks carried on the conveyor belt to hold the carton blanks against the conveyor belt.

4. A machine as in claim 2 which includes a main frame, means on the main frame for rotatably mounting the lower brush means adjacent the belt conveyor, an elevated frame pivotally mounted on the main frame for swinging above the lower brush means, means for rotatably mounting the upper brush means on the elevated frame, first motor means mounted on the main frame in driving relation to the lower brush means, second motor means mounted on the elevated frame in driving relation to the upper brush means, and means for limiting swinging of the elevated frame when the upper and lower brush means are opposed and in brushing relation to carton blanks carried by the belt conveyor.

5. In a machine for removing loose bits of paperboard from paperboard carton blanks, the combination of a first conveyor means, means for spreading the carton blanks on the first conveyor, a second conveyor means, the second conveyor means including a pair of belts, the pair of belts having converging sections adjacent a discharge end of the first conveyor and face-to-face sections thereafter, the face-to-face sections being at an obtuse angle to the direction of travel of the first conveyor, the first conveyor means projecting each carton blank between the converging sections to be engaged between the face-to-face sections, whereby the trailing edge of each carton blank is swung crosswise of the first conveyor, and brush means in the path of swinging of the trailing edge of each carton blank for brushing the loose bits of paperboard from the carton blanks.

6. A machine as in claim 5 wherein the brush means in the path of swinging is a rotary brush and means is provided for rotating the brush in a direction such that the portion of the brush which engages the carton blanks moves in a direction opposite to the direction of movement of the carton blanks.

7. A machine for removing loose bits of paperboard from carton blanks which comprises a frame, conveyor means mounted on the frame for transporting the carton blanks along the frame, the conveyor means gripping the carton blanks with side portions of the carton blanks extending outwardly of the conveyor means, a brush rotatably mounted on the frame in the path of the outwardly extending side portions, and means for rotating the brush as the carton blanks pass the brush, whereby the brush removes loose bits of paperboard from the side portions of the carton blanks.

8. A machine as in claim 7 wherein the conveyor includes two opposed belt conveyors which engage opposite faces of the carton blanks, and the belt conveyors travel transversely of and spaced from the axis of the brush.

9. A machine as in claim 7 wherein means is provided for advancing the brush toward and away from the conveyor means and crosswise of the direction of movement of the conveyor means.
